EGG CASE SEPARATOR

Harry E. Lambert, Gary, Ind., assignor to Packaging Corporation of America, Dover, Del., a corporation of Delaware

Filed Mar. 28, 1960, Ser. No. 59,880

Term of patent 14 years

(Cl. D58—13)

FIGURE 1 is a top plan view of an egg case separator, showing my new design;

FIG. 2 is an elevational view taken from the bottom of FIG. 1;

FIG. 3 is an elevational view taken from the right of FIG. 1; and

FIG. 4 is a vertical sectional view on the line 4—4 of FIG. 1.

FIGS. 2, 3, and 4 are on a scale larger than that of FIG. 1.

I claim:

The ornamental design for an egg case separator, substantially as shown and described.
